UNITED STATES PATENT OFFICE.

ALBERT H. TINNERMAN, OF CLEVELAND, OHIO.

COOK-STOVE-OVEN CONSTRUCTION.

Application filed August 20, 1923. Serial No. 658,281.

To all whom it may concern:

Be it known that I, ALBERT H. TINNERMAN, a citizen of the United States, residing at Cleveland, in the county of Cuyahoga and 5 State of Ohio, have invented a certain new and useful Improvement in a Cook-Stove-Oven Construction, of which the following is a full, clear, and exact description, reference being had to the accompanying drawings.

This invention relates to stoves of the type heated by hydro-carbon burners and is particularly concerned with an oven and broiler arrangement having walls and flues 15 so constructed as to produce the most efficient burning of the fuel and utilization of the heat.

In the construction of cook stove ovens, it is customary to provide an upright housing, in which is positioned, intermediately, a gas burner below the floor of the baking oven, and in the top of the broiling oven. The broiling oven is provided with a suitable support for a broiler tray which may 25 be positioned different distances below the burner. In the enclosing of the broiler and the oven in a unitary housing structure, difficulty is encountered in providing an effective air feed for the burner flame to accomplish perfect combustion without sacrificing heat, and of course, inefficient combustion results in producing offensive gases, moisture, condensation and the like, which is injurious.

The object of my invention is to provide 35 a simple and effective wall construction for the broiler and baking oven which may be cheaply manufactured and to arrange in this wall construction a system of air passages and flues to accomplish most effective 40 combustion and utilization of the heat without interfering with the usual necessary provisions such as named.

Additional objects include the provision 45 of an oven construction affording convenience in the removal of the floor of the oven, convenience of assembling of the parts within the oven, and including of straight flat panels on the exterior of the oven walls. Incidentally, the latter allows covering the 50 exterior with enamel, which is desirable.

Another object of the invention is to prevent the heat of the oven burners from being brought into direct contact with the oven walls at any concentrated point. Another 55 object is to provide a floor construction for the upper oven, whereby even distribution of

the heat is accomplished and yet direct heating of any part of the floor by concentrated application of the flame is prevented and even distribution of heat results.

Other objects of my invention will be hereinafter set forth in the following description which refers to the accompanying drawings illustrating a preferred embodiment thereof. The essential characteristics 65 are summarized in the claims.

In the drawings, Fig. 1 is a cross sectional side elevation taken through the oven structure of a gas stove embodying the features of my invention; Fig. 2 is a front elevation 70 cross section taken through the oven structure; Fig. 3 is a fragmentary perspective view of the top of the oven structure; Fig. 4 is an enlarged fragmentary cross sectional view of the upper front corner construction 75 of the oven; Fig. 5 is a cross sectional plan view taken substantially along the line 5—5 of Fig. 1; Fig. 6 is a perspective view of partitioning and flame impinging means for dividing the interior of the housing into a baking oven and a broiler oven; Fig. 7 is a cross section taken through the partitioning means shown in Fig. 6; Fig. 8 is a bottom plan view of the same.

It is the custom of stove manufacturers, in constructing cook stoves and gas ranges, to arrange the baking oven above the broiler oven whereby a single set of valves and burners may be utilized when using the 80 stove for baking or broiling or when simultaneously using both. This practice commends itself for the reason that the details of stove construction, particularly the oven construction, may be greatly simplified and incidentally effects an economy in the manufacture of the stove. Commercial demands 85 are such, however, that it is advantageous to supply a stove having the exteriorly exposed members thereof enameled or properly finished to facilitate cleaning. The fulfilling 90 of this demand by the manufacturer, particularly in the oven construction, introduces many difficulties including the proper distribution of heat so as to prevent concentration thereof at any particular place which 95 would result in discoloring or destroying the enameled finish.

In carrying out the objects of my invention, I provide an oven construction where all of the exterior members thereof are so formed that they may be enameled over all 100 their exposed surfaces and in addition there-

to may be assembled in the stove structure without the resulting exposure of bolt or clamping means. This I accomplish in the manner set forth in my patent application Serial No. 272,715 filed December 11, 1922, for Letters Patent on a stove construction.

The effecting of perfect combustion and the even distribution of heat generated thereby, I accomplish in the manner illustrated in Figs. 1 and 2, wherein I show a baking and broiler oven combined in a unitary housing structure. The front wall of this structure may comprise an oven door frame 10 and a broiler door frame 11 and the respective doors 12 and 13 therefor. The protection of the enameled fittings of this front frame structure is accomplished in the manner described and claimed in my patent application filed July 31, 1923, Serial No. 654,936 on a stove frame.

The rear and side walls of the oven structure include a heat insulating air space between the outer enameled panel members and the inner oven lining panels as shown in Fig. 1. The rear walls may comprise an outer enameled panel member 15, and an inner panel member 16, spaced therefrom to provide an air space 17. The side walls, as shown in Fig. 2, may comprise an outer panel member 20 and on the open burner side of the stove, outer panel members 21, 22, and inner panel members 23 and 24. These inner panel members are positioned in spaced relation to the panel members 20, 21 and 22 respectively, to provide heat insulating spaces 25 and 26. An outer top panel 30 may be provided with inwardly extending flanges 31 to engage corresponding flanges on the side panel members 19, 20 and 21 in the manner described and claimed in my first mentioned co-pending application.

This top panel member 30 bears a spaced relation to an inner top panel member 32, whereby a substantial flue gas space 33 is provided between the respective top panel members. A flue elbow 34 may be secured to the back panel member 15 adjacent the top thereof and in proper relation to a flue opening 35 formed therein. The outer panel members, as well as the front door frame, may be secured to a rectangular base band 36 which may be formed of bar iron of sufficient thickness to afford a substantially rigid support for the oven structure. This band may be directly mounted upon supporting legs 37. The space 17 between the rear panels 15 and 16 is enclosed at the bottom by a flange portion 16^a formed along the bottom edge of the panel 16 and a supporting angle member 36^b which may be secured to the inner face of the outer panel member 15 adjacent its lower end or to the band 36.

A removable broiler oven bottom 40 may

be formed as shown in Fig. 1 with downwardly extending flange portions at the front and back thereof engaging an extension in the form of an inner shoulder provided on the front door frame member 11 ⁷⁰ and the angle member 36^b. The side edges of the member 40 are spaced apart from the inner side panel members 23 and 24 to provide air passageways in a manner and for a purpose to be presently described. ⁷⁵ Spacer members in the form of angle strips 42 may be secured to the inner panel members with one leg thereof extending in the air spaces 17, 25 and 26 respectively. The side air spaces 25 and 26 are open at the bottom as indicated at 43 and 44 respectively in Fig. 2, and the spacer angles 42 are therefore extended to obstruct a too free movement of air through the spaces to the top flue space 33. Hence, I arrange the spacer angles 42 to extend substantially three fourths of the width of the spaces, leaving only free passage areas 46 and 47 adjacent the corners of the walls. ⁸⁵

The interior of the structure is divided by a partition wall disposed intermediate the baking oven door 12 and the broiler door 13. This wall may be a flame baffle, as well as a partitioning means dividing the interior of the structure into an upper baking oven O, and a lower broiler oven B. A hydro-carbon burner 50 may be disposed at the top of the broiler oven compartment with a mixed gas line 51 extending transversely toward the open burner side of the stove, whence a mixer 52 may be connected in the gas line of the stove to which the other mixers and burners (not shown) are connected. The burner 50 may thus serve as a boiler burner, as well as a baking oven burner, the heat being generated in the broiler and passing to the baking oven in the form of hot gases, through passageways formed in the side wall structures. ¹⁰⁰

To provide for this passage of heat from the broiler to the oven, I prefer to form the inner side panels 23 and 24 as shown in cross section in Fig. 2, whereby a substantial depression is formed in the panel members which extend from the bottom of the top thereof. I may thus form a passageway from the broiler oven to the baking oven in a very simple manner by securing sheet metal members 60 to the inner panel members so as to span these depressions as shown in Figs. 1 and 2. These sheet metal members may extend from immediately above the burners 50 toward the top of the oven and form hot gas passageways 63 leading from the top region of the broiler to the baking oven. The hot gases are thus guided through the passageways 63, to the top of the oven and circulate downwardly in the baking oven. The members 60 may be also suitably formed to have ribs which afford slideways ¹¹⁵ ¹²⁰ ¹²⁵ ¹³⁰

65 adaptable for the reception of utensil supporting grids or roast trays. Ribs 66 formed adjacent the lower ends of the members 60 afford shelves upon which the oven partitioning wall 67 may be removably positioned.

To prevent the radiation of heat through this partitioning wall, it may comprise, as shown in detail in Figs. 6 to 8 inclusive, as 10 asbestos boards 68, provided with a suitable sheathing or cover 69 forming the top thereof and incidentally the bottom surface of the baking oven portion. For convenience in cleaning, this upper sheet may be coated 15 with a vitreous enamel which is protected from the injurious effects of the heat by the insulating boards 68. The lower side of this partitioning wall preferably comprises a flame deflecting member 70 which is suitably 20 formed to provide a space 71 between the flame impinging portion thereof and the asbestos portion 68. This member may accordingly comprise a pressed metal sheet having a depressed central portion provided 25 with flanges 70^a around the ends thereof affording contact with the asbestos board. As shown in Fig. 7 suitable perforations 73 may be formed in the bottom member 70 to permit the circulation of the hot gases 30 between the asbestos board and the flame baffle member.

The members comprising this heat baffle wall may be secured together in any convenient manner such as by the use of stove bolts 35 72.

In order to obtain a proper combustion of the gas escaping from the burner, it is essential that a continuous supply of air be accessible to the burner. It has heretofore been the practice to either perforate the bottom panel member 40, or its equivalent in other structures, to permit this ingress of 40 fresh air or to form unsightly openings or perforations in the panel of the broiler door. 45 Both of these practices are objectionable for the reason that when the bottom of the broiler is perforated, the escape of grease from the oven is permitted, while forming 50 openings in the door does not give proper distribution of fresh air to the burner, particularly when the burners are properly disposed in the transverse position illustrated.

I effect a complete combustion of the gases by providing passageways which may be incorporated in the side wall construction of the broiler oven in a very economical manner. I find it convenient to utilize the structural provisions made in the side panels 23 and 24 for the formation of the passageways 63, in forming the broiler passageways 55 whereby they may extend from beneath the oven structure into the broiler oven. Thus by the use of broiler tray supporting members 75 which may be secured to the side 60 panels 23 and 24 in the same manner as the

members 60, I may form the passageways 76. The members 75 however, are provided with large openings 78 adjacent the lower ends thereof to permit a copious ingress of air to the burners. U-shaped baffle members 70 80 may be positioned in the depressions formed in the side panels 23 and 24 to completely obstruct any direct passage of air from the passageways 76 to the passageways 63. Since the passageway 76 extends 75 transversely relative to the burners 50, it will be readily seen that a uniform distribution of incoming air will be available at the burner flames under all conditions, as indicated by the arrows. 80

The U-shaped baffle members 80 may also be utilized as part of the securing means for maintaining the ribbed members 75 in position. The legs thereof may, therefore, be extended to be embraced by some of the rib 85 portions of the members 75. These ribs, of course, serve as broiler tray supports and may be formed on the members 75 at different elevations whereby slow or fast or intermediate broiling periods may be obtained regardless of the regulation of the 90 burner flame.

To permit the escape of the burned gases from the baking oven, I provide apertures 85 in the inner top panel 32 which are 95 formed therein adjacent the front of the oven structure and I provide a Z-shaped baffle plate 86, in the top space 33, to prevent the impinging of the hot gases upon the outer enameled panel 30. This baffle also 100 serves to direct the gases toward the flue 87.

A second baffle comprising a flanged plate 88 is disposed in front of an opening 89 formed in an upwardly extending flange 90 comprising one end of the inner top panel 105 32, the flange 90 serving to partition the top space 33 from the back space 17. A similar flange 91, is formed on the front end of the top panel member, and serves to prevent the impinging of the hot gases 110 against the top portion of the enameled front door frame 10. It will thus be seen that a complete cycle of gas movements include the mixing of gas and air at the mixer 52 and passage therefrom through the tube 115 51 to the burners 50, and the ingress of air to the burners through passageways 76 formed at each side wall of the oven, through the large openings 78 to the burner flames, from whence there is a deflection of 120 the hot gases by the plate 70 causing a downward and sideward circulation thereof. This cycle is completed by the escape of this hot burned gas upwardly through the passageways 63 toward the top of the oven from 125 whence they are deflected downwardly toward the baking trays of the oven. A partial escape of these hot gases through the openings 85 to the top space 33, takes place 130 and they then traverse this space to the flue 135

opening 35 formed in the outer back panel and escape therethrough into elbow 34 and chimney flue 87.

From the foregoing description of my invention, it is to be readily seen that I eliminate the disadvantages of a unitary oven housing construction wherein the broiler and baking oven are dependent for heat upon a single set of burners disposed in the 10 broiler, in that I provide a very simple wall construction which incorporates therein air passageways establishing communication from outside of the stove to the interior of the broiler which permits the ingress of 15 a copious and fresh supply of oxygen to the broiler burner in an even and uniform manner. The burned gases are thereafter directed upwardly through similar passageways which are formed in the oven walls 20 in an extremely simple economical manner, from a manufacturing viewpoint.

This upper oven wall construction affords passage for hot gases only as direct air passage from the exterior of the stove to the 25 upper oven is prevented by reason of the disposition of the baffles in the passageways intermediate the top and bottom of the broiler. Thus the baking oven walls have only hot gases contacting therewith in the 30 top passageways which are extended upwardly a considerable distance to prolong the transference of heat thereto. This construction it will be seen furthers the obtaining of proper combustion conditions as only 35 the desired amount of air will be drawn to the burners.

Furthermore, it will be seen that I provide a very simple removable partitioning wall which defines the baking oven and 40 broiler oven and which is constructed in such manner that the top surface thereof may comprise the bottom or floor of the baking oven and may be enameled thereby

permitting ready cleaning thereof. This construction, it may be seen, is such that the 45 enamel will not be destroyed despite the impinging of the burner flames upon the under or broiler side thereof. This partition also serves to direct the hot gases to passageways leading from the broiler to the 50 baking oven. It will also be seen that I incorporate the above enumerated advantageous feature of hot gas circulation in a stove construction in such manner as to permit the enameling of all the outer exposed members of the oven structure, while preventing destruction or damaging of this 55 finish by the elimination of all heat concentrations at any particular point.

Having thus described my invention, I 60 claim:

A cooking range construction comprising a double wall baking and broiler oven construction formed by inner and outer vertically disposed panel members spaced from 45 each other and open at the top and bottom to form air passages, two of said inner panel members being oppositely disposed and having vertically extending depressions therein 50 forming passageways establishing communication between the exterior of the structure and the boiler oven and between the boiler oven and baking oven, a spacing member baffles disposed between the inner and outer panel members, obstructing the too free passage of air from the bottom to the top of the structure, an inner top oven panel member extending over the depressed ends of 55 said inner side members and terminating short of the outer side panels whereby free 60 passageways for cool air are afforded at the corners of the oven structure.

In testimony whereof, I hereunto affix my signature.

ALBERT H. TINNERMAN.
